UNITED STATES PATENT OFFICE.

GEORGE S. GATCHELL, OF ROSELLE PARK, NEW JERSEY, ASSIGNOR TO THE SINGER
MANUFACTURING COMPANY, A CORPORATION OF NEW JERSEY.

THREAD-CONTROLLING MECHANISM FOR MULTIPLE-NEEDLE SEWING-MACHINES.

1,397,507.

Specification of Letters Patent.

Patented Nov. 22, 1921.

Application filed September 25, 1919. Serial No. 326,290.

To all whom it may concern:

Be it known that I, GEORGE S. GATCHELL, a citizen of the United States, residing at Roselle Park, in the county of Union and 5 State of New Jersey, have invented certain new and useful Improvements in Thread-Controlling Mechanisms for Multiple-Needle Sewing-Machines, of which the following is a specification, reference being had therein 10 to the accompanying drawings.

This invention relates to thread-controlling mechanism for multiple-needle sewing machines, more particularly of the type represented in my copending application Serial 15 No. 185,446, filed August 10, 1917, and my United States Patent No. 1,361,247, of December 7, 1920.

In a multiple-needle single-looper machine, wherein the needles are arranged close 20 together, it is necessary to control the needle-threads with a high degree of nicety at certain critical periods of the stitch-forming cycle if high speed operation is to be attained, and in my prior machine I have provided a series of rotary thread-controlling cams for closely and individually controlling 25 the needle-threads. By carefully shaping these cams, the desired accuracy of control of the needle-threads can be obtained under 30 a given set of operating conditions, *i. e.*, for a given stitch-length in work of a given character. When sewing work of a different character, however, or when the stitch-length is altered, slight changes are introduced in 35 the requirements for perfect needle-thread control and the machine is liable, at times, to produce malformed stitches or break thread under high speed operating conditions.

40 An object of the present invention, therefore, is to provide needle-thread controlling mechanism for multiple-needle machines which will control the needle-threads with a uniform degree of accuracy at the critical 45 periods of the stitch-forming cycle under the various operating conditions to which the machine is likely to be subjected in practice.

More particularly, the invention has for 50 an object to provide means for maintaining an even strain or tension upon the needle-thread loops which are about the looper at the period of the cycle when the looper is retracting and the descending needle points 55 are about to pass their respective needle-

loops. If the needle-loops are too tight at this time they will tend to assume positions too far forward on the looper. If too loose, they will be dragged too far rearwardly. In other words, if the tension on the needle-loops is not very nearly what it should be, the needles are likely to split the thread of or enter their respective previously formed loops instead of passing down beside said loops, as is essential to the formation of 60 65 perfect stitching.

To the attainment of these ends, I have combined with suitable positively acting take-up means, such, for example, as disclosed in my prior applications, a series of 70 individual yielding devices for placing a light drag upon the respective needle-threads at certain periods of the stitch-forming cycle to absorb possible slack thread between the take-ups and the work and to give up thread 75 under a possible abnormal strain. These devices function, together with the take-up means, to maintain a uniform tension on the needle-threads at the critical periods of the stitch-forming cycle under all the various 80 operating conditions met with in practice.

In the accompanying drawings, Figure 1 is a side elevation of the machine embodying the invention. Fig. 2 is a top plan view of the forward part of the bracket-arm of the 85 machine. Fig. 3 is a fragmentary side elevation of the parts shown in Fig. 2 at a period of the cycle when the needle-bar is rising. Fig. 4 is a view similar to Fig. 3 at a period of the cycle when the needle-bar is 90 descending. Fig. 5 is a front end elevation of the bracket and work-arms showing the yielding thread-controlling devices; the needle being at the end of its down stroke and the looper being fully retracted. Fig. 6 is a 95 similar view at a slightly later period of the cycle when the needles are rising and the looper has entered well into the first needle-loop and is just entering the second needle-loop. Fig. 7 is a view similar to Figs. 5 and 100 6 but showing the needle-bar near the upper end of its stroke and the looper near the end of its advancing stroke. In this figure the needle-threads are shown as released by the yielding thread-controlling devices preparatory to the action of the needle-bar in pulling thread from the supply. Fig. 8 shows the thread-controlling devices with the needle-bar at the upper end of its stroke. Fig. 9 shows the needle-thread under the 105 110

control of the yielding thread-controlling devices as the descending needles are about to pass their respective previously formed loops on the retracting looper; the position being the same as in Fig. 4. Fig. 10 is a detail perspective view of two of the yielding thread-controlling devices arranged on a common support. Fig. 11 is a front elevation of a modified form of yielding thread-controlling device and Fig. 12 is a large diagrammatic view of the needle-thread take-up cams with which the present machine is equipped.

In the preferred embodiment of the invention, as illustrated, the machine is constructed substantially in accordance with the disclosure of my said copending applications and comprises a frame formed with a base, not shown, from which rises the standard 2 carrying the forwardly extending hollow work-supporting arm or horn 3 and the superposed bracket-arm 4 terminating in the hollow head 5 in which is journaled the reciprocating needle-bar 6 carrying the eye-pointed needles n^1 , n^2 , n^3 and n^4 . The needle bar is actuated by means of the usual pitman connection 7 with the crank-arm 8 at the forward end of the oscillatory needle-driving shaft 9 which extends within and lengthwise of the bracket-arm 4 and is connected with the crank 10 upon the main-shaft 11 in any suitable manner.

Coöperating with the needles is the thread-carrying looper 12 which is mounted 35 on the looper-carrier 13 fixed to the forward end of the usual rocking and sliding shaft 14 extending lengthwise of and within the work-supporting arm 3. It will be understood that the shaft 14 is rocked to give the 40 looper 12 the usual loop-seizing and shedding movements and is moved endwise to give the looper the usual sidewise or so-called "needle-avoiding" movements.

The machine is preferably equipped with 45 the usual differential feeding mechanism including the fulling and main feed-dogs 15 and 16, respectively, and with suitable presser and covering thread mechanisms including the presser-foot 17 and covering thread fingers 18, all as more fully described in my said copending application Serial No. 185,446.

The present machine, like my said prior machine, is provided with a set of individual 55 needle-thread controlling cams c^1 , c^2 , c^3 and c^4 which operate, respectively, upon the needle-threads t^1 , t^2 , t^3 and t^4 . Each of these cams preferably comprises two similar spaced disks formed as usual with a common 60 hub. These cams are mounted on the cam-shaft 19 which is journaled in the thread-controller frame 20 secured to the top side of the bracket-arm 4 and is driven by a one-to-one bevel-gear connection 21 with the upper 65 end of the inclined shaft 22 inclosed within

the shaft casing 23. The lower end of the shaft 22 is connected to the main-shaft 11 by means of the one-to-two speed multiplying bevel-gears 24 and the two-to-one speed reducing spur-gears 25 and is thus driven at 70 the same speed as the main-shaft 11 in order that the take-up cams may perform one rotation for each stitch-forming cycle.

Coöperating with the cams c^1 , c^2 , c^3 and c^4 are the usual thread-guiding forks 26 and 75 stripper-plates 27; the former serving in the usual manner to guide the needle-threads across the active peripheral portion of their respective cams and the latter to cause the needle-threads to be deflected radially of 80 said cams.

Coöperating with the thread-controlling cams is a series of thread-nippers 28 which are more fully described in my said copending application and serve to lock the needle-threads while the needle-loops are being tightened after having been shed by the looper. 85

Mounted on top of the bracket-arm at the rear of the machine is the tension frame 29 carrying a plurality of tension devices 30 for the various sewing threads.

The needle-bar 6 is provided at its upper end with a multiple thread guide comprising a horizontal bar 31 having individual needle-thread eyes 32. A bar or thread-stop 33, the elevation of which is controlled by the thickness of the work as described in my said copending application Serial No. 185,446, is provided to assist in measuring thread from 95 the supply when the needle-bar approaches the upper end of its stroke.

All of the foregoing features of construction are present in my prior machine, as disclosed in my said copending applications 105 and, as has been stated, the take-ups or thread-controlling cams, under a given set of operating conditions, are so shaped as to control the needle threads with the required high degree of accuracy so that the machine 110 will perform satisfactorily at high speed. The thread-control requirements, however, for a four-needle seam of the character made by the present machine, are so exacting that it has not been found possible to design a set 115 of average cams which will control the needle-loops with sufficient accuracy under the various operating conditions met with in practice.

A machine of the present character is intended for use in sewing up knitted under-wear and should be able to handle thick or thin work with equal facility, as well as to "chain off" with no work in the machine or sew at any stitch-length adjustment within 120 the range provided. The present improvement is intended to insure equal treatment of the needle-threads under various operating conditions at certain critical periods in the 125 stitch-forming cycle as, for example, when 130

the points of the descending needles are about to pass their respective previously formed loops on the retracting looper-blade, and as the advancing looper is seizing the 5 needle-loops.

In the particular embodiment of the invention chosen for the purpose of the present disclosure, the improvement comprises individual yielding thread-engaging devices 10 d^1, d^2, d^3 and d^4 which are associated in pairs with the supports 34 and 35. Each of the supports 34, 35 is in the form of an up-standing post having side surfaces 36 arranged in parallel vertical planes. The 15 posts 34, 35 are mounted at the top of the front side of the head 5 and extend upwardly from said head closely in rear of the horizontal bar 31 of the thread-guiding bracket, as shown in Fig. 3. The parallel side surfaces 36 of the posts 34, 35, are disposed, respectively, in planes substantially coincident with the vertical paths of movement of the thread-eyes 32 in the bar 31, so that, as the bar 31 reciprocates, the needle-thread 20 lengths between the take-ups c^1 to c^4 , inclusive, and the thread-eyes 32, wipe over the respective surfaces 36.

The surfaces 36, of themselves, offer no resistance to the free movement of the needle-thread either up and down or toward and from the needles. In order, however, to impose a light yielding drag or thread absorbing action upon the needle-threads at certain periods of the stitch-forming cycle, the 30 series of spring-fingers or yielding thread-engaging devices d^1, d^2, d^3 and d^4 is provided. As these spring-fingers are similarly constructed and mounted on the posts 34, 35, a description of one will suffice. Referring to Fig. 9, for example, the spring d^4 is in the form of a flat blade, the shank of which is provided with a vertical slot 37 through which passes the clamping screw 38 threaded into the post 35. A similar slot 39 is formed 40 in the finger d^4 above the slot 37 to fit over the steady pin 40. This construction provides for vertical adjustment of the various fingers on their supporting posts.

From its lower end the spring d^4 extends 50 upwardly a certain distance to the offset 41 where it is bent inwardly into contact with the surface 36 of the post 35. From the offset 41, the spring d^4 extends upwardly in light contact with the surface 36 to the offset 55 42 where the spring is bent outwardly to clear the surface 36. From this point the spring extends upwardly to its reduced free end which is received between the guiding ears 43 on the post 35. It is understood that 60 the springs d^1, d^2 and d^3 are constructed similarly to the spring d^4 and are provided with the active thread-engaging portions between the offset points or bends 41 and 42.

Referring to Figs. 4 to 8, inclusive, it 65 will be seen that the offsets 41 of the springs

are arranged at progressively higher elevations beginning with the spring d^4 , while the offsets 42 are all arranged at substantially the same elevation. The purpose of this construction will be clear from the following description of the operation of the machine.

Starting at the position shown in Figs. 8 and 12, with the needles up and the looper fully advanced, as the needles descend the 70 looper begins its retracting stroke and the outwardly inclined portions of the cams c^1-c^4 at the left of the thread-guiding forks 26, Fig. 12, operate to absorb the needle-thread given up by the descending thread-eyes 32 in the bar 31 and prevent the formation of slack thread below the needles. When the needle-points enter the work, however, the thread-eyes 32 reach the position shown in Fig. 7 and carry their respective needle-threads below the inward bends 42 of the 80 yielding thread-controlling fingers d^1-d^4 , whereby said fingers impose a light drag or yielding thread absorbing action upon the respective downwardly-moving needle-threads by pressing them against the surfaces 36 of the posts 34, 35. This drag causes the needle-threads to be deflected more or less between the cams c^1-c^4 and the thread-eyes 32, thus absorbing a little 90 slack-thread and maintaining an even or uniform tension on each of the previous needle-loops about the looper.

As the peaks u^1, u^2, u^3 and u^4 pass the vertical position or line of stationary thread-eyes in the forks 26, the needle-threads t^1-t^4 100 are successively slackened as the respective needle-eyes descend below the work; the cams c^1-c^4 being shaped in the present instance to afford a slight excess of slack 105 thread which is absorbed by the yielding devices d^1-d^4 . It will be seen that the effect of these yielding devices is to deflect the needle-threads upwardly between the take-ups c^1-c^4 and the thread-eyes 32, as shown 110 in Fig. 4. A uniform strain is thus imposed upon the needle-threads at this time by the devices d^1-d^4 and this strain is substantially independent of the stitch-length as well as the thickness or character of the 115 work being stitched. In other words the devices d^1-d^4 impose a substantially uniform tension on the needle-threads during the descent of the needles regardless of variations in the amount of slack-thread which 120 may make its appearance between the take-ups c^1-c^4 and thread-eyes 32 due to variations in sewing conditions. The more slack there is in the needle-threads, the greater will be the upward deflections imposed by 125 the devices d^1-d^4 and vice versa. The needle-loops on the retracting looper will thus be subjected to a uniform tensioning action under all conditions and will invariably assume evenly spaced positions, as shown in 130

Fig. 9, beside their respective needle-paths, so that each of the descending needles will pass its previously formed loop without entering or splitting the thread of such loop.

5 As soon as the needle-points descend well below their respective previously formed loops, the thread-eyes 32 carry the needle-threads below the thread-engaging portions of the springs d^1-d^4 , and as the needle-loops 10 are shed from the looper, they are successively tightened by the outward inclines on the take-up cams between the points v^1-v^4 and w^1-w^4 , respectively, as described in my said copending applications. When the 15 needles reach the end of their down stroke and the looper is fully retracted, Fig. 5, the cams c^1-c^4 have rotated 180°.

As the needles rise they present their loops to the advancing looper; it being understood 20 that the loops of the needles n^2 , n^3 and n^4 are suitably reduced in size by their respective cams c^2 , c^3 and c^4 prior to the seizure of such loops by the looper. One of the chief causes 25 of failure of machines of the present character to perform satisfactorily is the tendency of the advancing looper to drag the previously seized needle-loop into a subsequently seized loop, whereby certain of the needle-loops are crossed on the looper and cause malformed 30 stitching if not thread breakage. In my prior machine, the individual rotary take-ups were depended upon to maintain their respective needle-loops snugly about the looper-blade during its loop-seizing stroke. 35 While these cams can, with care, be designed to accomplish this result satisfactorily, under a given set of operating conditions, it is found that variations in sewing conditions such as commonly met with in garment factories, introduce slight variations in the requirements for accurate thread-control, so 40 that a given set of cams may not, of themselves, control the needle-threads with the high degree of accuracy required at this 45 period of the stitch-forming cycle under variations in operating conditions.

For this reason the needle-thread controlling devices d^1-d^4 are made use of to successively tighten or snub the needle-loops about the looper-blade as the latter seizes 50 said loops, so that a previously seized needle-loop cannot be dragged into a loop about to be seized. Referring to Fig. 6, it will be seen that the point of the advancing looper 55 has entered well into the loop of needle n^1 and is just entering the loop of needle n^2 . At this time the rising needle-bar 6 has carried the thread-eyes 32 as high as the inwardly directed bend 41 of the spring d^1 , where- 60 upon further upward movement of the needle-bar will cause the thread t^1 to be instantaneously tensioned by the spring d^1 . The loop of the needle n^1 will thus be brought under the yielding control of the spring d^1 at the 65 correct instant of time and, it is evident,

that the spring d^1 will maintain said loop lightly but snugly about the looper-blade and prevent it from being dragged into the loop of needle n^2 .

In a similar manner, the successively 70 higher bends 41 of the springs d^2 , d^3 and d^4 operate upon the threads t^2 , t^3 and t^4 to successively tension the needle-loops during the advance of the looper. Variations in sewing 75 conditions will have no appreciable effect 80 upon the action of the devices d^1-d^4 in controlling the needle-loops during their seizure by the looper for the reason that they are so designed and so related to the take-up eyes 85 32 as to come abruptly into action at the correct successive instants of time and to suddenly impose the desired light tension on the respective needle-loops regardless of 90 whether the work be thick, thin, springy or relatively unyielding. 95

After the looper has reached the position shown in Fig. 7, the needle-threads are carried above the thread-engaging portions of the spring-fingers d^1-d^4 and further upward movement of the thread-eyes 32 serves 90 to pull thread from the supply for the next stitch.

The thread-controlling devices may, if desired, be made up in the form shown in Fig. 11. In this form the post 45 is provided with 95 offsets 46 and 47 which are similar, respectively, to the offsets 41 and 42 previously described. The springs 48 are doubled upon themselves at 49 and are secured at the lower ends of their outer limbs to the post 45. The inner limbs 48' of the springs bear lightly 100 against the opposite side surfaces of the post 45 between the offsets 46 and 47, as will be readily understood. The lower ends of the inner limbs 48' are freely received between 105 guide wings 50. In this construction the springs exert a somewhat more nearly uniform pressure upon the needle-threads throughout their movement over the active length of the pressure exerting surfaces than 110 is the case with the single springs.

While I have shown and described one specific embodiment of the invention, it is to be understood that the invention is not limited to the specific form and arrangement 115 of parts herein disclosed. Various modifications, substitutions, rearrangements, &c., may be readily made by one skilled in the art, in the light of the present disclosure, without departure from, or sacrifice of the 120 advantages of the invention.

Having thus set forth the nature of the invention, what I claim herein is—

1. A sewing machine having a plurality of needles set in a plane crossing the line of 125 feed, a looper coöperating therewith to form stitches, means for tightening the needle-loops as they are shed from the looper, and yielding means disposed out of engagement with the needle-threads at the beginning of 130

the down-stroke of the needles and adapted to come into engagement with the needle-threads as the needles descend and uniformly strain the needle-threads as the descending 5 needle-points pass their respective previously formed loops on the looper.

2. A sewing machine having a plurality of needles set in a plane crossing the line of feed, a looper coöperating therewith to form 10 stitches, means for tightening the needle-loops as they are shed from the looper, and yielding devices disposed out of engagement with the needle-threads when the needles are at the end of their down-stroke and adapted 15 to engage the needle-threads as the needles rise and successively tighten the needle-thread loops as they are seized by the advancing looper.

3. A sewing machine having a needle-bar, 20 a plurality of needles carried by said bar and set in a plane crossing the line of feed, a looper coöperating with said needles to form stitches, multiple thread guiding means carried by the needle-bar, take-up devices co- 25 operating with said thread guiding means for successively tightening the needle-loops as they are shed from the looper, and yielding thread deflectors disposed out of engagement with the needle-threads at the begin- 30 ning of the down-stroke of the needles and adapted to come into engagement with the transversely moving needle-thread lengths extending between the take-up devices and the needle-bar to uniformly tension the 35 needle-threads as the descending needle-points are passing their respective previously formed loops on the looper.

4. A sewing machine having a needle-bar, a plurality of needles carried by said bar and 40 set in a plane crossing the line of feed, a looper coöperating with said needles to form stitches, multiple thread guiding means carried by the needle-bar, take-up devices co- 45 operating with said thread-guiding means for successively tightening the needle-loops as they are shed from the looper, and yielding thread deflectors disposed out of engagement with the needle-threads when the needles are at the top and bottom of their strokes and 50 arranged to act upon the transversely moving needle-thread lengths extending between the take-up devices and the needle-bar to uniformly tension the needle-threads as the descending needle-points are passing their re- 55 spective previously formed loops on the looper, said deflectors being adapted to successively engage the needle-threads during the upward motion of the needle-bar to successively tighten the needle-loops as they are 60 seized by the advancing looper.

5. A sewing machine having a reciprocating needle-bar, a plurality of needles carried by the needle-bar and set in a plane crossing the line of feed, a looper coöperating with 65 the needles to form stitches, multiple thread

guiding means on the needle-bar, take-up means coöperating with said thread-guiding means for successively tightening the needle-loops as they are shed from the looper, and a plurality of yielding thread engaging de- 70 vices in addition to the take-up means for imposing a transverse wiping action upon the vertically moving portions of the needle-threads in rear of said multiple thread guid- ing means.

6. A sewing machine having a reciprocating needle-bar, a plurality of needles carried by the needle-bar and set in a plane crossing the line of feed, a looper coöperating with the needles to form stitches, multiple thread-guiding means on the needle-bar, take-up means coöperating with said thread-guiding means for successively tightening the needle-loops as they are shed from the looper, and a plurality of yielding thread engaging de- 75 vices disposed out of engagement with the needle-threads when the needles are at the lower end of their stroke, said devices being arranged each in the path of movement of a respective needle-thread and adapted to act 80 yieldingly and to successively tighten the needle-loops as they are seized by the looper.

7. A sewing machine having a plurality of needles set in a plane crossing the line of feed, a looper coöperating therewith to form 95 stitches, thread-handling devices acting to move certain portions of the needle-threads transversely of the direction of their extent during the tightening of the previously formed needle-loops shed by the looper, and 100 a plurality of yielding thread engaging de- vices having coacting nipping surfaces, the planes of which coincide respectively with the paths of transverse movement of the needle-threads; said devices being adapted 105 to assume yielding control of the needle-threads as the needle-points are passing their respective previously formed loops on the looper.

8. In a sewing machine, in combination, a 110 plurality of needles, a looper, take-up means for reducing the sizes of certain of the needle-loops prior to their seizure by the looper, and a plurality of yielding thread-engaging devices out of engagement with the needle-threads during the first part of the up-stroke of the needles and adapted to successively tighten the needle-loops on the looper-blade during the loop-seizing stroke.

9. In a sewing machine, in combination, a 115 plurality of needles, a looper, take-up means for reducing the sizes of certain of the needle-loops prior to their seizure by the looper, and a plurality of yielding thread-engaging devices arranged out of contact with the needle-threads during the action of the take-up means in reducing said needle-loops, said devices having off-set portions arranged at different elevations so as to come successively into action and tighten 120 125 130

the needle-loops as they are seized by the looper.

10. Thread controlling mechanism for multiple needle sewing machines comprising, a reciprocating needle-bar, a multiple thread guide carried thereby, a plurality of individual rotary thread controlling cams adapted for differential control of the needle-threads, and a plurality of individual yielding thread-engaging devices having active portions arranged at different elevations and adapted to come successively into action on the needle-threads during the upward movement of the needle-bar.

15. 11. A yielding thread controlling device for multiple needle single-looper sewing machines comprising, a post having spaced thread engaging surfaces at opposite sides thereof, and a plurality of yielding spring devices carried by said post and adapted to press against said surfaces, the opposed surfaces at one side of the post being greater in active length than at the other side.

12. A yielding thread controlling device for sewing machines comprising a post having a thread-engaging surface, a spring having a pair of limbs extending side by side and joined at their upper ends, the lower end of the outer limb of said spring being rigid with said post and the inner limb of said spring being adapted to bear yieldingly against said thread-engaging surface.

13. A sewing machine having a plurality of reciprocating needles set in a plane crossing the line of feed, a looper coöperating therewith to form stitches, a set of individual rotary cams for differentially controlling the needle-threads, and a set of individual yielding devices, arranged out of effective engagement with their respective needle-threads when the needles are at the upper and lower limits of their stroke and adapted to be successively engaged by the needle-threads as the corresponding needle-loops are seized by the advancing looper.

14. A sewing machine having a plurality of needles set in a plane crossing the line of feed, a single looper coöperating therewith

to form stitches, a set of tension devices, a set of individual thread-cams adapted for differential control of the needle-threads, and a set of yielding needle-thread engaging devices operatively separated from said cams, and disposed between the needles and the tensions.

15. A sewing machine having a plurality of needles set in a plane crossing the line of feed, a single looper coöperating therewith to form stitches, means including a set of individual rotary cams for successively tightening the needle-loops as they are shed by the looper, and a set of yielding slack-thread controlling devices adapted to co-operate with said cams in successively and uniformly tightening the needle-loops upon the looper-blade as they are seized by the latter, regardless of variations in sewing conditions.

16. Thread controlling mechanism for multiple needle, single-looper sewing machines comprising, a plurality of thread-cams adapted for differential control of the needle-threads and a plurality of yielding slack-thread controlling devices associated with said cams, substantially as and for the purposes specified.

17. A sewing machine having a plurality of needles set in a plane crossing the line of feed, a single-looper coöperating therewith to form stitches, a plurality of individual thread-controlling cams adapted for differential control of the needle-threads, a plurality of yielding thread engaging devices, multiple thread guiding means associated with said thread-engaging devices, and means for relatively moving said thread-guiding means and devices transversely of the needle-threads, whereby to secure a wiping action of the needle-threads over the thread-engaging surface portions of the thread-engaging devices in directions transverse to the lead of the needle-threads.

In testimony whereof, I have signed my name to this specification.

GEORGE S. GATCHELL.
